UNITED STATES PATENT OFFICE

JOHN S. HAUG, OF PHILADELPHIA, PENNSYLVANIA, ASSIGNOR TO UNITED ENGINEERS & CONTRACTORS INC., OF PHILADELPHIA, PENNSYLVANIA, A CORPORATION OF DELAWARE

GAS GENERATOR GRATE HAVING ADJUSTABLE ECCENTRICITY

Application filed September 3, 1929. Serial No. 339,885.

The present invention relates to rotating mechanical grates for gas generators.

The object of the invention is the provision of means for readily varying the degree of eccentricity of a mechanical grate with respect to its axis of rotation.

It is desirable in the operation of a gas generator to be able to use efficiently a variety of fuels and to this end it is desirable to provide means for varying the action of the mechanical grate.

In the use of fuels producing large amounts of hard clinker, it is necessary for the grate to exert considerable crushing action on the clinker and this may be effected by providing the grate with considerable eccentricity, the grate crushing the clinker between itself and the generator wall.

With fuels producing less hard clinker, this eccentricity may be reduced, while with the most desirable fuels from a clinker standpoint, satisfactory operation may be secured with a grate concentric with its axis of rotation.

The variation of generator operating conditions, such as, for instance, the maximum temperature attained in the fuel bed during the operating cycle, if it is a water gas generator, may also make desirable the varying of the eccentricity of the grate.

The crushing action of an eccentric grate results in considerable wear on the grate itself and therefore it is not desirable to set the grate with greater eccentricity than is required by the character of the fuel and operating conditions.

In the present invention I provide simple and effective means for readily varying the eccentricity of the grate to meet varying clinker crushing requirements.

The invention will be described in connection with the accompanying drawing which forms a part of this specification and in which,

Figure 1 shows a vertical cross section of the lower portion of a gas generator provided with a rotatable mechanical grate, shown in partial elevation, and partial vertical cross section, and illustrating the present invention

with the grate concentric with its axes of rotation.

Figure 2 shows a partial horizontal cross section along the line 2—2 in Figure 1.

Figure 3 shows a partial horizontal cross section similar to Figure 2, but with the grate set for the maximum provided eccentricity.

Referring to Figures 1, 2 and 3,

1 generally indicates the outside or fire wall of the generator, bounding the fuel space

2. 3 indicates the grate, which is mounted on the ash pan 4, and secured thereto by the bolts 5 extending through bolt holes arranged at equal intervals in circles on the grate and the ash pan. The ash pan and grate are provided with suitable means for rotation, as for instance, the worm wheel 6 driven by the worm 7 mounted on the shaft 8 which is driven by a motor, not shown, the ash pan and grate rotating on the bearings 9. These means for rotation are indicated in Figure 1 as is the plough 10 for removing ash and clinker from the ash pan to the ash pocket 11. The gas producing fluids such as air and steam are introduced to the interior grate through the duct 12 simultaneously in producer operation or alternately as in water gas operation and pass thence through the fuel bed. 13 generally indicates a seal.

The bolt circle of the ash pan is arranged eccentrically with respect to the axis of rotation which is indicated as B—B in Figure 1 and as B in Figures 2 and 3. The axis of the bolt circle of the ash pan is indicated as the line C—C in Figure 1 and C in Figures 2 and 3.

The bolt circle of the grate is arranged eccentrically with respect to the axis of the grate in the same degree that the bolt circle of the ash pan is eccentric to the axis of rotation of the ash pan and grate.

By arranging the grate on the ash pan so that the eccentricities of the two bolt circles oppose each other, the axis of the grate coincides with the axis of rotation and the grate is concentric. This arrangement is shown in Figures 1 and 2.

By unbolting the grate and revolving it on the ash pan 180 degrees from the position of Figures 1 and 2, the position indicated in

Figure 3 is attained in which the eccentricities of the two bolt circles supplement each other so that the axis of the grate indicated as D is eccentric with respect to the axis of rotation B, by the sum of the eccentricities of the bolt circles, or since they are equal, by twice the eccentricity of the grate with respect to its axis.

Intermediate eccentricities of the grate with respect to the axis of rotation may be attained by revolving the grate to a less or greater extent than 180 degrees. The number of intermediate eccentricities attainable depends on the number of bolt holes in the bolt circles. In Figures 2 and 3, three intermediate positions are provided.

I claim:

1. In a gas generator provided with a mechanical grate, means for varying the eccentricity of the grate with respect to its axis of rotation, comprising, an ash pan supporting the grate and having a circle of bolt holes therein arranged eccentrically with respect to the axis of rotation, and a grate having a circle of bolt holes therein arranged eccentrically with respect to the axis of the grate.

2. In a gas generator, means for varying the crushing action exerted upon the clinker, comprising a mechanical grate, a support having a circle of bolt holes therein, means for rotating the grate and the support, said mechanical grate having a circle of bolt holes therein cooperating by means of bolts with the circle of bolt holes in the support, the circle of bolt holes on the grate being arranged eccentrically with respect to the axis of the grate, and the circle of bolt holes in the support being arranged eccentrically to the axis of rotation, whereby the eccentricity of the grate with respect to the axis of rotation may be varied.

3. In a gas generator, means for varying the crushing action exerted upon the clinker, comprising a mechanical grate, a support having a circle of bolt holes therein, means for rotating the grate and the support, said mechanical grate having a circle of bolt holes therein cooperating by means of bolts with the circle of bolt holes in the support, the circle of bolt holes on the grate being arranged eccentrically with respect to the axis of the grate, and the circle of bolt holes in the support being arranged eccentrically to the same degree to the axis of rotation, whereby the eccentricity of the grate with respect to the axis of rotation may be varied.

4. In a gas generator, means for varying the crushing action exerted upon the clinker, comprising a mechanical grate, an ash pan having a circle of bolt holes therein, means for rotating the grate and the ash pan, said mechanical grate having a circle of bolt holes therein cooperating by means of bolts with the circle of bolt holes in the ash pan, the

circle of bolt holes in the grate being arranged eccentrically with respect to the axis of the grate, and the circle of bolt holes in the ash pan being arranged eccentrically to the axis of rotation, whereby the eccentricity of the grate with respect to the axis of rotation may be varied.

5. A gas generator having means for varying the eccentricity of the grate with respect to its axis of rotation comprising in combination, a rotatable support having fastening means thereon eccentric to the axis of rotation of the support, and a mechanical grate having fastening means thereon eccentric to the axis of the grate and adapted to cooperate with the fastening means on the support to secure the support and the grate together.

6. Ash supporting means for a combustible gas generator, said means comprising in combination a rotatable grate having a plurality of fastening means arranged in a circle thereon eccentric to the axis of said grate, and an ash pan adapted to support said grate thereon and having a plurality of cooperating fastening means thereon arranged in a circle eccentric to the axis of rotation of said ash pan.
